UNITED STATES PATENT OFFICE.

NATHANIEL FROST, OF BLOOMINGTON, ILLINOIS.

WATER-CLOSET.

No. 863,977.

Specification of Letters Patent.

Patented Aug. 20, 1907.

Application filed July 2, 1906. Serial No. 324,360.

To all whom it may concern:

Be it known that I, NATHANIEL FROST, a citizen of the United States, and a resident of Bloomington, in the county of McLean and State of Illinois, have invented 5 a new and Improved Water-Closet, of which the following is a full, clear, and exact description.

The invention relates to that class of water closets in which the bowl is automatically flushed when the occupant rises from the seat.

10 The purpose of the invention is to provide an automatic double-acting valve adapted to be used preferably in connection with an air-tight tank, but which may be connected with any other form of tank if desired, the valve being so arranged that the seating or 15 unseating thereof is not dependent upon springs as is usually the case, the only spring employed being an auxiliary medium for normally holding the seat elevated for ventilating purposes and when the water pressure is insufficient, the principal medium to such 20 end, however, being the water pressure in the valve.

Another purpose of the invention is to provide a sanitary construction of the bowl, which bowl is so arranged at the rear as to form a ventilating chamber for carrying off offensive odors which are usually allowed 25 to escape into the room.

Another purpose of the invention is to provide a flushing valve which will be simple and positive in operation and economic and durable in construction, and one wherein the water pressure is utilized to normally 30 keep the valve closed, the valve being opened automatically by the pressure exerted on the seat by the occupant thereof.

The invention consists in the novel construction and combination of the several parts, as will be hereinafter 35 fully set forth and pointed out in the claims.

Reference is to be had to the accompanying drawings forming a part of this specification, in which similar characters of reference indicate corresponding parts in all the figures.

40 Figure 1 is a vertical section through the improved closet and valve, the parts being in normal position; Fig. 2 is an enlarged vertical section through the valve of the closet and adjacent portion of the bowl, showing the valve opened for admission of water to the flushing 45 tank; Fig. 3 is a horizontal section through the device looking upward, the section being taken practically on the line 3—3 of Fig. 1; Fig. 4 is a vertical transverse section taken substantially on the line 4—4 of Fig. 3, and Fig. 5 is a detail sectional view of the rear end of 50 the bowl and its shield showing the connection between the vent box and bowl.

A represents the bowl of the closet, which is provided at the rear with a jet pipe 10, and the outlet 11 of the pipe 10 is at the rear bottom portion of the bowl proper. The bowl A is provided with a curved partition 12,

which extends downwardly and rearwardly from the front, and the said partition also extends from side to side of the bowl, its upper face being concaved. The bottom 14 proper of the bowl, extending from the rear to the front below the partition 12, forms a chamber or 60 channel 15 between it and the partition 12; but the said channel 15 is open at its upper end, being connected directly with a discharge tube or channel 16 formed integral with the bowl, by means of a suitable outer member 13, extending from the upper portion of the 65 partition 12 downward to a connection with the sewer or drain pipe.

A metal shield 17 is made to rest upon the upper edge of the bowl, and that portion of said shield which extends at the sides and front of the bowl is curved downward and somewhat inward as shown in Fig. 1, so that when water is directed to the inner member of the said shield the water will be forced to flow down the sides of the bowl and thus tend to wash it at such point. The shield 17 is provided at its rear with a wide horizontal 70 flat extension 17^a, and the rear continuation 19 of the forward and side sections 17 of the said shield is closed at the bottom, as shown in Fig. 3, and is connected with a tube or chamber 20, which is formed at the lower central portion of the flat upper extension 17^a of the said shield, 75 as is shown in Figs. 1 and 4. This chamber 20 extends out through the rear of the bowl, and is connected at its rear portion with the upper end of the jet pipe 10, as is shown in Figs. 1 and 2; and the outer end of this chamber 20 is connected with a flushing valve B to be hereinafter described. The rear closed section 19 of the shield 17 is provided with downwardly-extending 80 tubes 21, so that the water entering the chamber 20 and passing around the rim, a side and forward portion of the shield, in addition to passing down at the inner 85 sides of the bowl will be directed downward so as to effectually wash the rear inner wall of the bowl, as is shown in Figs. 1 and 3. The seat 22 is of the usual construction, and is preferably secured to a skeleton metal frame 23. This frame has a hinge connection 24 at its 90 rear usually with the said upper extension 17^a of the shield 17 for the bowl, as is shown in Fig. 1.

A pin 25 extends down from the rear central portion of the seat 22 or its supporting frame 23, as is shown in Figs. 1, 2 and 3; and this pin 25 opens the flushing 100 valve B when the seat is occupied, since at such time the pin 25 bears against a roller 26 located at the inner end of a plunger rod 27, which extends through and has guided movement in the water-receiving or flushing chamber 20, as particularly shown in Figs. 1 and 2. 105 The outer end of the plunger rod 27 is preferably reduced in diameter and is encircled by a spring 29, which is located in a rear pocket 30 formed in the bottom or main casing 28 of the said flushing valve B, and this pocket is provided with a removable cover in order 110

that ready access may be gained to the spring when desired. An angle lever 32 is fulcrumed in the lower or main casing 28 of the flushing valve B, its horizontal member being uppermost; and the lower portion of the 5 vertical member of said lever is pivotally connected with said spring-controlled plunger rod 27. The lower or main casing 28 of the flushing valve B is provided with an intermediate tubular vertical section 33 which connects with the upper portion of the lower or main 10 casing 28, and likewise with an upper chamber 34 provided preferably with a removable cover. This chamber 34 has a suitable connection 35 with a source of water supply.

A valve seat 36 is formed in the upper chamber 34 15 where it connects with the intermediate member 33 of the flushing valve casing; and a second and lower valve seat 37 is provided where the said intermediate member 33 connects with the lower or main section 28 of the said valve casing, as is shown in Figs. 1 and 2. 20 The stem of a valve 38 slides freely in the intermediate member 33 of the valve casing B, as also shown in Figs. 1 and 2, and said valve stem is provided with a lower head 39 adapted for engagement with the lower seat heretofore mentioned. Said lower head 39 of the valve 25 likewise rests upon the horizontal member of the lever 32 connected with the plunger rod 27. A second and upper head 40 is secured to the stem of the said valve 38, and said upper head 40 is adapted for engagement with the upper seat 36 in the upper chamber 34 of the 30 valve, and when one of the heads of the valve is seated the other is unseated. In the open position of the valve, or that which permits water for flushing purposes to be introduced through the valve from a source of supply, the upper head 40 is unseated as shown in Fig. 2 35 and the lower head 39 is seated; at such time the water will flow through the upper chamber 34 of the valve casing and its intermediate member 33 into a pipe 41 which is connected with the said intermediate member 33 of the valve casing at a point above the lower seat 40 37. This pipe 41 is connected with a flushing tank 42, said tank being preferably air-tight, although it is not absolutely necessary that it should be so made. The open position of the valve is taken when the seat 22 of the closet is occupied, and the pin 25 carried by said 45 seat forces the plunger rod 27 rearward, thus causing the lever 32 to force the valve 38 upward, as is clearly shown in Fig. 2; and as soon as the seat is unoccupied the spring 29 acts to force the plunger rod inward or to its normal position, permitting the valve 38 to close, 50 the actual closing of the valve being brought about by the pressure of the in-coming water.

A vent box 43 is erected at the rear of the closet, being preferably placed upon the shield extension 17^a of the bowl shield 17; and said vent box is provided with a 55 pipe 44 at its lower end, preferably oval in cross section. This pipe is connected with the extension 17^a of the shield 17 at a suitable opening therein as shown by dotted lines in Fig. 3, so that the inlet pipe 44 connecting with the vent box 43 is connected with the bowl A 60 at each side of the flushing chamber 20. Consequently the odors as the flushing operation takes place are forced upward into the vent box 43, and said vent box 43 has a connection 45 with a heated flue or other form of flue which will induce draft. Therefore the closet is rendered hygienic, since the odors which ordinarily escape,

into the room are conducted off therefrom, and each and every portion of the bowl are thoroughly cleaned by the flushing or in-coming supply of water.

In the detail operation of the closet, when the seat is occupied the valve 38 is forced upward so that its lower 70 head is seated and its upper head is unseated, whereupon the water entering the valve casing is forced up into the tank 42; but the moment the seat is relieved from pressure the valve seats itself at its upper head and unseats itself at its lower head, and the water will 75 immediately flow from the tank 42 into the lower portion of the valve casing and from thence into the jet pipe 10 and to all the outlets in the flushing shield.

The closet is preferably made of enameled cast iron; but without departing from the spirit of the invention 80 and with slight changes in form, the closet may be made of earthenware, in which event the jet pipe 10 will be made integral with the bowl.

Having thus described my invention, I claim as new, and desire to secure by Letters Patent,—

1. In a water closet, a closet bowl, a hinged seat, a valve casing having two chambers connected by a reduced tubular portion, one of the chambers being connected with the bowl and the other with a source of water supply, a double headed valve having a head in each chamber with 90 its stem extending through and sliding freely in the reduced portion of the casing, a tank connected with the said reduced portion of the casing, a sliding and spring pressed rod actuated by the seat, and a pivoted lever having one end operatively connected with the sliding rod and 95 its other end adapted to engage the valve to operate it.

2. In a water closet, a closet bowl, a hinged seat, a valve casing connected with the bowl and with a water supply, a freely sliding double headed valve in the casing, a tank connected with the casing between the heads of the 100 valve, a sliding and spring pressed rod actuated by the seat, and a pivoted angle lever having one member pivoted to the said rod and its other member engaging the valve when the seat is occupied and disengaged therefrom when the seat is unoccupied.

3. In water closets, a bowl, a hinged seat therefor, a chambered flushing shield for the said bowl, a valve casing connected with said flushing shield, a valve within the said casing, having opposing heads, one of which is seated when the other is unseated, a source of water supply for the valve casing, located above the upper head of the valve, a tank, a connection between the tank and the valve casing between the seats of the valve, a plunger operating in the flushing shield and valve casing, means for imparting end movement to the plunger by the raising and lowering movement of the seat, and a lift lever for the valve, controlled by the movement of the plunger.

4. In water closets, a bowl, a hinged seat therefor, a chambered flushing shield for the said bowl, a valve casing connected with said flushing shield, a valve within the said casing, having opposing heads, one of which is seated when the other is unseated, a source of water supply for the valve casing, located above the upper head of the valve, a tank, a connection between the tank and valve casing between the seats of the valve; a plunger mounted 120 on slide in the valve casing and in the flushing shield where it connects with said casing, a spring normally forcing said plunger forward, an extension from the seat for engagement with the forward end of the plunger; a lever fulcrumed in the valve casing and pivotally connected with the said plunger, which lever is in engagement with the lower head of the valve, whereby the valve is closed from the top by water pressure and is closed from the bottom by the operation of the said plunger.

5. In water closets, a bowl, a flushing shield for the 135 bowl, having a chamber at its rear, said shield being open at the bottom at its front and its sides, tubular extensions from the chamber of the said shield, a valve casing connected with the chambered portion of the flushing shield, a double-headed valve mounted in the said casing, a source 140

of water supply located above said valve, a tank, a connection between said tank and the valve casing, which connection is between the heads of the valve, a spring-controlled plunger mounted to slide in the valve casing below the valve and in the chamber of the said flushing shield, a lever pivoted in the valve casing, connected with said plunger, which lever is arranged for engagement with the lower head of the valve, and an extension from the closet seat which engages with the inner end of the plunger, operating the same to seat the bottom head of the valve when the seat of the closet is pressed downward, said spring serving to return the plunger to normal position when the pressure on the closet seat is removed.

6. In a water closet, the combination of a bowl, a chambered flushing shield for the bowl, said shield having an extension at its rear, a flushing chamber connected with the shield and opening into the bowl, a vent box on the extension of the shield, and a pipe connecting the box with the bowl at each side of the flushing chamber. 15

In testimony whereof I have signed my name to this 20 specification in the presence of two subscribing witnesses.

NATHANIEL FROST.
